UNITED STATES PATENT OFFICE.

THEODORE CORNUELLE, OF CINCINNATI, OHIO.

PROCESS FOR MAKING CONCRETE BLOCKS.

1,233,847.

Specification of Letters Patent. Patented July 17, 1917.

Application filed September 8, 1915. Serial No. 49,609.

To all whom it may concern:

Be it known that I, THEODORE CORNUELLE, a citizen of the United States, residing at Cincinnati, in the county of Hamilton and 5 State of Ohio, have invented certain new and useful Processes for Making Concrete Blocks, of which the following is a specification.

My invention relates to the process of 10 making concrete building blocks to imitate solid rock.

Concrete blocks as is well known, are made by various methods, the most common being to face the block after it has been cast 15 or molded. This facing of the block often adds greatly to the cost of the construction by increasing the time and labor thereon, but requires considerable skill to do properly and to produce a correct and accurate re- 20 semblance of stone.

It is the object of this invention to provide a process for making concrete blocks which will, it is believed, produce blocks with a face as near in appearance and as 25 perfect a resemblance to stone as it is possible to produce, no two being alike.

The process consists in casting the blocks in pairs, preferably, or in a series, and providing a series of wedges which are placed 30 between the blocks, that is, at their point of connection at the time of molding, and then by means of these wedges, fracturing the castings into individual blocks, thereby producing blocks, the faces of which are 35 produced by fracture. This it will be evident produces a block with a face the exact appearance of a fractured stone face.

My invention further consists of the method described including the various steps 40 in the process as will be hereinafter set forth and pointed out in the appended claims.

In the accompanying drawings which serve to illustrate my invention and which show a preferred form—

Figure 1 is a perspective view of the mold used in my improved process for making concrete blocks.

Fig. 2 is a vertical cross sectional view of same.

Fig. 3 is a perspective view of the frame used in the mold.

Fig. 4 is a modification showing wedge plates which may be used in place of the frame shown in Fig. 3.

Fig. 5 shows a perspective cross section of a block as it comes from the mold.

Fig. 6 is a side elevation of a block after it has been fractured showing the pitching tool in place ready to pitch finish the edge of the block.

Fig. 7 is a perspective view of the completed block.

Referring more particularly to the drawings, 1 represents the floor or bottom of the mold in which the blocks are cast. The side 65 boards 2 are placed parallel with one another, and the dividing strips 3 are inserted in slots 4 in the side strips, the tongues 3' extending into said slots. Frames 5 are then placed on top of this construction upon 70 which wedges 6 are laid. These wedges extend outwardly a short distance and inwardly, or toward each other a short distance beyond the inner edges of the plates. Another frame 5 is then placed on top of 75 the wedges 6 upon which another set of boards or sides 2 and strips 3 are placed. Then concrete constituting a finishing material is poured in to a point about three inches above the plates. This finishing material may be of any color, and consistency 80 to represent any kind of stone desired, fine or coarse grained, then the rest of the mold is filled up with the concrete first used. This provides about six inches of fine concrete 85 through which the fracture takes place, and thereby produces a face showing material of the consistency desired.

The frames 5 are constructed preferably of steel, having a thick edge portion 8, and 90 a thinner extension 9 extending toward the center. The frame is open at the center as shown in Fig. 3.

The frames 5 may be constructed without the thick edges if desired as shown in Fig. 3. 95 When the frames 5 are used a shoulder 10 is molded on the block as shown in Figs. 5 and 6. This shoulder is then pitched off after the stone has been divided by fracturing approximately along the dotted lines 100 shown in Fig. 5. The pitching is done by means of a pitching tool such as is shown in Fig. 6. This operation finishes the face of the stone and adds to its appearance.

When the frames 5' are used without the 105 thick edges as shown in Fig. 4, the blocks are cast without the shoulders 10. Then after the blocks are fractured or broken in half, the edges are chipped or pitched off by means of the pitching tool which puts a 110 finish on the block and does away with the small flat margin 20 so commonly found in

manufactured blocks. The pitching of the edges also serves to rid the block of any trace of the wedges and therefore this step in the process is termed the finishing. The frames or plates as shown in Fig. 4 are wedged shaped in themselves and therefore it is not necessary to provide the extra wedge between the plates, but by tapping the plates themselves, the block is readily broken.

10 When these plates are used, they are not fastened together to form a complete rectangular frame, but are each inserted individually at their proper points, therefore each can be tapped independently of the other.

When the boards 2 for the outside mold are placed one upon the other, the bars 21 are inserted through suitable loops on the sides of said boards in order to hold them in position.

After the blocks have been fractured the wedges fall out of place or can be easily removed. The pitching is then done by means of the pitching tool which breaks the shoulder approximately along the dotted lines thereon in Fig. 6.

What I claim as new and desire to secure by Letters Patent is:

1. The process of making concrete building blocks, consisting of casting them together with wedges extending a short distance therein at their points of connection, and then dividing the blocks by tapping on

the wedges, thereby fracturing the blocks, the fractured surfaces constituting the faces 35 of the blocks.

2. The process of making concrete building blocks, consisting of casting them together with wedges at their point of connection, then dividing them by tapping the 40 wedges and causing a fracture of the block, then pitching off the shoulders left at the edges of the fractured faces by the molds.

3. The process of making concrete building blocks, consisting of casting them in a 45 mold together, with wedges inserted around the edges at their point of connection, then dividing the blocks before they are thoroughly dry by tapping on the wedges, thereby fracturing them, and then pitching the 50 edges of the fractured faces of the blocks to produce a finish.

4. The process of making concrete building blocks, consisting in building up a mold in which a number of blocks may be cast together with wedges extending a short distance in the sides at their point of connection, and then filling the molds with wet concrete with a suitable quantity of fine cement connecting the blocks together; then 55 allowing them to dry a short time; then dismantling the molds, then tapping the wedges lightly, dividing the blocks by fracture and then pitching around the edges of the fractured faces of the blocks.

THEODORE CORNUELLE.
